UNITED STATES PATENT OFFICE

FREDERICK CHARLES HOHENSTEIN, OF DUNKIRK, NEW YORK

HYDROCARBON BURNER AND HEATER

Application filed April 30, 1930. Serial No. 448,760.

This invention relates to a hydrocarbon burner and heater, the general object of the invention being to provide means whereby liquid fuel and air are heated by the burner and introduced into a manifold from which the mixture is introduced by a nozzle into the burner, with means for mixing air with the mixture of fuel and preheated air as it enters the burner, so that the mixture will be highly combustible and thus a heater and burner of great efficiency is obtained.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is an elevation with the housing for the burner and its coils in section.

Figure 2 is a plan view of the invention, with parts in section.

Figure 3 is a section on line 3—3 of Figure 2.

In these views, the numeral 1 indicates a balancing reservoir into which oil or the like is pumped through the pipe 2 which contains the valve 3. This reservoir is fastened to a supporting member by the brackets 4 and a burner 5 is supported from the reservoir by the brackets 6. A manifold 7 is supported from the reservoir by the brackets 8 and a nozzle 9 is connected with the front of the manifold and extends into a rearwardly flaring part 10 connected with the rear end of the burner, the nozzle being connected with said part 10 by the strips 11, so that air can enter the burner between the nozzle and the part 10 so as to mix with the combustible mixture passing from the nozzle and more air can enter the rear of the burner through the arc-shaped slots 12 therein.

Tubes 13 are connected with the top of the reservoir and one of these tubes is coiled around the front part of the burner, as shown at 14, and the other tube is coiled around the

rear part of the burner, as shown at 15, and after being so coiled, the tubes are carried rearwardly, as shown at 16, to the ends of the manifold, where they are connected with the nozzle members 17 which are arranged in the manifold and have their nozzle extremities curving forwardly at approximately an angle of 45° toward the nozzle 9, as shown at 18, so as to force the vapor into the nozzle 9. A pipe 19 leads from a source of compressed air and is coiled in longitudinally extending convolutions about the burner, as shown at 20, and then the pipe is extended rearwardly, as shown at 21, where it is connected with the coupling 22 which in turn is connected with the valve casing 23 and the said casing is connected by a pipe 24 with a nozzle 25 in the manifold, the extremity of this nozzle 25 being arranged between the nozzle extremities 18 of the fuel pipes.

A housing 26, preferably composed of copper and asbestos, surrounds the burner and the coils so as to confine the heat from the burner around the coils. Thus the air and oil in the coils are highly heated from the heat from the burner and also by the heat escaping through the staggered holes 27 in the burner and the preheated air and oil are mixed in the manifold, which acts as a balancing medium and this combustible mixture escapes through the nozzle 9 into the burner, where it is ignited. As the mixture flows into the burner, it draws atmospheric air through the slots 12 and the space around the nozzle 9 and the member 10 so that the mixture has great combustible qualities as the oil is vaporized by passing through the coils 14 and 15. By increasing the air supply, the temperature is increased to a high degree which automatically converts the burner into a blow torch or heater and the combination of the oil balancing reservoir 1, the two spirally wound oil coils 14 and 15, the air coils 20, the housing enclosing the coils and burner and the mixing and reserve manifold, produces a burner of the greatest efficiency. The arrangement of the nozzles 18 and 25 produces a proper mixture of the air and oil vapor and directs the mixture through the nozzle 9 into the burner. It is thought from the foregoing descrip-

tion that the advantages and novel features of the invention will be readily apparent.

It is to be understood that changes may be made in the construction and in the combination and arrangement of the several parts, provided that such changes fall within the scope of the appended claim.

What I claim is:

A device of the class described comprising
10 a reservoir, means for introducing liquid fuel under pressure into the same, a burner, two sets of coils extending around the burner, means for connecting one end of each coil to the reservoir, a manifold, nozzle members
15 passing through the ends of the manifold and having their inner ends shaped to provide forwardly curved nozzles, means for connecting the other end of each coil to said nozzle members, longitudinally extending coils arranged around the burner, means for connecting one end of said last mentioned coil to a supply of compressed air, a nozzle in the manifold and extending forwardly from the rear thereof with its outlet and arranged be-
20 tween the curved nozzles, means for connecting the air coils with said nozzle, an outlet nozzle connected with the manifold and ar-
25 ranged to receive the fuel and air from the nozzles in the manifold, said outlet nozzle be-
30 ing arranged in the burner and spaced from the rear part thereof whereby air can enter the burner through the space between the outlet nozzle and the rear part of the burner and slots in the rear part of the burner for the
35 admission of air and a housing surrounding the burner and the coils.

In testimony whereof I affix my signature,
FREDERICK C. HOHENSTEIN.
